UNITED STATES PATENT OFFICE.

LAFAYETTE STANTON, OF BEAVER RIVER, NEW YORK, ASSIGNOR OF NINETY-FIVE ONE-HUNDREDTHS TO HIMSELF AND FIVE ONE-HUNDREDTHS TO FORSYTH MANUFACTURING COMPANY, OF BUFFALO, NEW YORK, A DOMESTIC CORPORATION.

LINE-WIRE FASTENER.

No. 888,763.

Specification of Letters Patent.

Patented May 26, 1908.

Application filed August 1, 1907. Serial No. 386,537.

To all whom it may concern:

Be it known that I, LAFAYETTE STANTON, a citizen of the United States, residing at Beaver River, in the county of Herkimer and 5 State of New York, have invented certain new and useful Improvements in Line-Wire Fasteners, of which the following is a specification.

My invention relates to improvements in 10 fasteners or clamps especially for applying telegraph, telephone or other line wires to their insulators as in suspending the same in position from poles or other supports. Its objects are mainly to obviate winding 15 pieces of wire around the line-wire after passing the same around the insulator, as in fastening or connecting the line-wire to the insulator; to provide for rendering the work of attaching and detaching the line-wires ex- 20 tremely rapid; to prevent mutilating or kinking the line-wire; to provide for effectively securing or fastening the line-wire to the insulator; and to carry out the aforesaid ends in a simple and economic manner.

25 Said invention consists of certain features or instrumentalities substantially as herein-after fully disclosed and specifically pointed out by the claims.

In the accompanying drawing illustrating 30 the preferred embodiment of my invention— Figure 1 is a front elevation thereof as applied to a cross-arm of a telephone pole. Fig. 2 is a side elevation of the same devoid of pole cross-arm. Fig. 3 is a plan view of the parts 35 as disclosed by Fig. 2.

In the disclosure of my invention, I employ an arcuate plate-member 1 preferably of 40 sheet metal and adapted to conform and be applied to the ordinary insulator used upon telegraph poles or telephone line or other supports for the line-wire. Said member has its arms provided with oppositely ex- 45 tending lateral terminals 2 each provided with an elongated slot 3, the purpose of which will presently appear.

A clamp-member 4 preferably of stout wire and of practically U-form, is adapted to have its arms passed through the elongated slots 3 of the lateral terminals 2 of the plate-member 1. Said clamp-member has its arms extended to form lateral hooked terminals 5, which, however, are arranged at right-angles to the terminals 2 of the plate-member 1 and are adapted to receive or en-

gage the line-wire and clamp it against said 55 terminals 2 and thus provide for securing the line-wire firmly therebetween. A cam-lever 6, having its cam or eccentric portion presented toward, and adapted to bear upon the plate-member 1 about central of the convexity thereof, has pivotal connection with the clamp-member 4 close to its back edge. 60

It will be noted that, with the device suitably applied to the insulator, as indicated in the several figures, the hooked terminals 5 65 are caught over the line-wire which is received in the annular groove of the insulator, and that, by then suitably actuating the cam-lever 6 the clamp-member 4 will be drawn upon so as to cause its said terminals 70 to grip the line-wire and clamp it against the terminals 2 of the member 1, thus providing for clamping and securing said line-wire effectively in place upon the insulator.

It will be understood that the device re- 75 mains as a fixture at all times upon the insulator, and that, in addition to possessing the advantages as above recited, by its use a great saving of time and labor in "construction work" is effected; that firmness and ef- 80 ffectiveness of grip are secured, and that repairs or alterations may be readily made. It is also noted that a further advantage of the use of this device is due to the fact that it is devoid of any large flat or projecting parts 85 which would otherwise catch and retain snow, ice or water, and thereby become clogged.

The device, which may be designated generally as a clamp, it will be noted, comprises 90 a plurality of members which are conformed to the insulator and are provided with means for gripping or engaging the line-wire and are so movable relatively to each other that they are caused to clamp both the line-wire and 95 the insulator.

I claim—

1. A line wire fastener comprising two clamps, the ends of one extending through the ends of the other and receiving the wire 100 and a lever for forcing the clamps apart and creating pressure upon the wire.

2. A line wire fastener comprising two U-shaped clamp members, one having slots at its ends through which the ends of the other 105 clamp extend, and one constructed at its ends to receive the line wire and a lever for applying pressure in to the clamps in opposite di-

rections whereby the line wire is clamped and held fast between the four ends of the two clamps.

3. A device as described, comprising a plurality of clamp-members adapted for application to a line-wire insulator, one of said members being arcuate in outline and having lateral terminals provided with elongated slots, and the other clamp-member having 10 its arms passed through said slots and provided with hook-ended terminals arranged at right angles to the terminals of the aforesaid member, said terminals being effective for gripping the line-wire, and a cam-lever having 15 pivotal connection with the clamp-member having the hook-ended terminals.

4. A device as described, comprising an arcuate clamp-member having slotted outstanding or lateral terminals, an additional 20 clamp-member having hook-ended terminals

passed through said slotted lateral terminals, said terminals effective for clamping or gripping the line-wire between them, said clamp-members being adapted for application to a line-wire insulator, and a cam-lever having 25 pivotal connection with said hook-ended clamp-member.

5. A device as described comprising two U-shaped clamps, one constructed and adapted at the ends to receive a line wire there-through and the other to press against said line wire, and means pressing against said clamps to create this clamping pressure upon the wire. 30

In testimony whereof I affix my signature, 35 in presence of two witnesses.

LAFAYETTE STANTON.
